CARRIAGE CONTROLLED STOP SETTING
AND KEY OPERATING MECHANISM FOR
TYPEWRITING MACHINES

Ferdinand J. Tillman, St. Louis, Mo.

Application June 25, 1942, Serial No. 448,375

13 Claims. (Cl. 197—1)

1

The primary object of the invention is to provide a simple means to limit the return movement of the typewriter platen carriage each time to the column next to be operated in until the items of that account are entered.

Another object is to provide a locking means for the typewriter platen carriage until the Star Clear Key is printed.

Other and further objects will appear in this specification, and will be specifically pointed out in the appended claims, reference being had to the accompanying drawings exemplifying this invention and in which:

Fig. 1 is a front elevation in part of the typewriter calculating machine partly broken away, showing the platen carriage return stop mechanism, the star key stop release mechanism, the date key operating mechanism, and stop setting mechanism.

Fig. 2 is a side elevation in part of Fig. 1.

Fig. 3 is a bill computed on the machine.

Referring to the drawings (see Fig. 1) A is the typewriter, the lower part of the typewriter being broken away, as this invention pertains to a locking and releasing mechanism for the typewriter platen carriage in cooperation with certain typewriter keys.

The typewriter has the usual keys 69. On the left side of the key board is a special star printing key 196 to indicate that the register is clear. On the right side of the key board is a special date printing key 156.

The typewriter has the usual platen carriage B with a platen B—1 mounted in the side frames B—2 and B—3. Guide rods B—4 and B—5 also mounted on the side frames B—2 and B—3 (see Fig. 2) are slidably mounted in tracks A—7 and A—8 mounted on top of the typewriter side frames A—5 and A—6 (see Fig. 1). A pull tape 1 is attached at 2 to the side frame B—3 and the other end of the pull tape 1, is attached to a spring drum C, to propel the typewriter carriage to the left. The typewriter has the usual escapement that limits the travel of the platen carriage to a step by step movement when it is being propelled to the left by the tape 1 and the drum C.

Limiting the back travel of the typewriter carriage

A slide plate 168 provided with two slots 169 and 170 is mounted on the plate 161 by guide pins 171 and 172 formed on the front plate 161.

On the right end of the slide plate 168 are two upwardly extending cams 173 and 174, which straddle the lower arm of a bellcrank 175 piv-

oted at 176 to the front plate 161. The upper end of the bellcrank 175, which is in alignment with a stop pawl 178, has a stop abutment 177 and a locking abutment 177a. The stop pawl 178, which is pivoted at 179 to the front plate 166 of the platen carriage, is provided with a spring 181 to hold the pawl in operative position against a limiting pin 180. The pawl 178 which is in alignment with the stop abutments 177 and 189 is free to move over the abutments when the carriage moves to the left but will stop the carriage from moving to the right when the stop abutments are locked in set position by the slide 168. The stop abutment 189 is a part of the bellcrank 187 that is pivoted at 188 to the front plate 161 of the typewriter and is provided with a locking abutment 189a. The lower arm of the bellcrank is straddled by two upwardly extending cams 185 and 186 which are similar to the cams 173 and 174.

It will now be understood that if the slide plate 168 is moved to the left (by mechanism to be described) the stop abutments 189 and 177 will be moved into alignment with the stop pawl 178 that is carried by the platen carriage and the platen carriage will be prevented from being pulled back from the left to the right beyond these stop abutments until the slide plate 168 is again moved to the right and allows the stop abutments 189 and 177 to be lowered out of alignment with the stop pawl 178 carried by the platen carriage. The slide plate can be moved back to the left so as to place the locking abutments 189 and 177 in the path of the stop pawl 178 either by operating the date key 156 or by pulling back the platen carriage to the right as will now be described.

On the rear of the plate 166 carried by the typewriter carriage is a roller 165, this roller 165 being in alignment with the top arm 164 of a bellcrank. This bellcrank lever is loosely pivoted at 163 to the rear of the plate 161 and has a lower arm 162 upon which a pin 159 is securely fastened. The pin 159 extends through a slot 160 in the plate 161 and carries a link 158 which is attached to a date key. The bellcrank lever has an extension arm 182 and a pin 183 is firmly attached to the extension arm 182, the pin 183 extending through a slot 184 in the front plate 161. This pin 183 is in alignment with the right end of the slide plate 168, and whenever the date key is operated or the platen carriage is pulled far enough to the right for the roller 165 to engage the upwardly extending arm 164 it will cause the pin 183 on the extension arm 182 to

move the slide plate 168 to the left so the stop abutments 189 and 177 will be placed in alignment with the stop pawl 178 and the typewriter platen carriage will be stopped in that position whenever it is moved to the right against either of the said abutments 189 or 177.

Releasing the stop abutments

On the left side of the typewriter (as shown in Fig. 1) is a bellcrank having an upper arm 193 and a lower arm 191 pivoted at 192 to the front plate 161. The upper arm 193 is provided with a pin 193a which extends through a slot 194 in a pull rod 195 connected to the star printing key 196.

It will now be understood that when the star key 196 is operated the pull rod 195 will cause the upper arm 193 of the bellcrank to be moved downward and the lower arm 191 will move the slide plate 168 to the right so the stop abutments 189 and 177 will be lowered out of alignment with the stop pawl 178 and the typewriter carriage can be moved to the right until the roller 165 again engages and moves the upper arm 164 so the date will print and the stop pawl 178 will again be in alignment with the stop abutments 189 and 177.

The complete operation

The paper is inserted into the platen carriage and adjusted to the proper line, and the platen carriage is then moved to the right and the date key is operated to print the date upon contact of the roller 165 with the lever 164. The stop abutments are also set up through roller 165 (as shown in Fig. 1). The old balance 00.00 is then written. "Room" is written and the amount (see Fig. 3) of the debit 3.00 is written. The typewriter platen carriage is then pulled back until the stop pawl 178 engages the stop abutment 177 which is the item column. "Rest" and the amount 1.65 are written and the carriage returned so that the stop pawl 178 engages the stop abutment 177. "Bar" and the amount 4.75 are written and the carriage is again returned so that the stop pawl 178 engages the stop abutment. "Misc." and the amount 2.25 are written and the carriage tabulated to the credit column. As there is no credit .00 is written and the carriage moves to the new balance column where 11.65 is written and the star key is pressed. If the register is at zeros the star key will print a star, but if the operator forgets to press the star key the typewriter platen carriage will be held by the stop abutment 189 until she does press and print the star key.

What I claim is:

1. In combination, a calculating machine having key levers, a traveling platen carriage, means to propel the carriage in one direction, stop abutments adapted to be set in a plurality of zones to limit the return movement of the carriage, setting means for said stop abutments, means on the carriage for cooperation with said setting means, and releasing means for said stop abutments under the control of one of the key levers.

2. A typing machine having key levers, a carriage, means to propel the carriage in one direction, a stop to limit the return movement of the carriage, setting means for said stop having cooperation with one of the key levers, means on the carriage to actuate said setting means, and key operated means remote from said one key lever for releasing said stop.

3. A typing machine having a frame, a carriage

5 on the frame having means for propelling it in one direction, a stop on the frame to limit the return movement of the carriage, key levers, setting means cooperable with one of the key levers and said stop, and means on the carriage to actuate said setting means and the key lever cooperable therewith.

4. A typing machine having a frame, a carriage on the frame having means for propelling it in one direction, a releasable stop on the frame to limit the return movement of the carriage, key levers, setting means cooperable with one of the key levers and said stop, means on the carriage to actuate said setting means and the key lever cooperable therewith, and key operated releasing means for said stop.

5. A typing machine having a frame, a carriage on the frame and means for propelling it in one direction, a plurality of stops, a slide member on the frame for setting and unsetting said stops, 20 a pawl borne by the carriage for cooperation with said stops, a key lever cooperable with one end of said member to set the stops, and a key lever cooperable with the opposite end of said member 25 for unsetting the stops.

6. A typing machine having a frame, a carriage on the frame having means for propelling it in one direction, a releasable stop on the frame to limit the return movement of the carriage, setting means cooperable with said carriage and said stop, means on the carriage to actuate said setting means, key operated releasing means for said stop, and key operated means cooperable with said setting means.

35 7. A writing machine having a platen carriage, a stop borne by said carriage, a pair of stops positioned for aligned cooperation with said carriage stop, simultaneous setting means for said pair of stops, a key lever, and actuating means 40 for said setting means cooperable with both said carriage and said key lever at the end of the carriage return movement.

8. A writing machine having a platen carriage, a pawl borne by said carriage, a pair of permanently spaced stops positioned for aligned cooperation with said pawl, simultaneous setting means for said pair of stops, a key lever, actuating means for said setting means cooperable with both said carriage and said lever at one end 45 of the carriage travel, and other means cooperable with said setting means for unsetting said pair of stops at the other end of the carriage travel.

9. A writing machine having a platen carriage, 55 a pawl borne by the carriage, a pair of stops fixedly positioned for aligned cooperation with said pawl, simultaneous setting means for said pair of stops actuated by the carriage at one end of its travel, and means for unsetting said pair of stops at the other end of the carriage travel.

10. A writing machine having a platen carriage, a pawl borne by the carriage, a plurality of permanently spaced stops positioned for aligned cooperation with said pawl, simultaneous setting means for said plurality of stops actuated by the carriage, and other means comprising a key lever for unsetting said setting means.

11. A writing machine having a platen carriage for letter spacing and return movements, a frame, a plurality of horizontally aligned and permanently spaced pivoted stops mounted on the frame, a stop borne by the carriage for cooperation with said frame stops, means paralleling said carriage for swinging and holding said frame stops in co-operating alignment with said carriage stop,

means borne by the carriage for actuating said swinging means on the return movement of the carriage, and key operated means cooperable with said swinging means for disengaging said frame stops from cooperating alinement with said carriage stop.

12. In a writing machine, a frame, a carriage mounted on the frame for letter spacing and return movements, a stop borne by the carriage, a plurality of permanently spaced horizontally alined stops mounted on the frame with which the carriage stop is cooperable, setting means for the frame stops paralleling the carriage and operated by said carriage on its return movements, and other means operable for upsetting said stop setting means at the end of the carriage letter spacing movements.

13. A writing machine having a carriage, permanently spaced columnar stops, means operable by the carriage on its return movement for setting said stops, and yieldable stop means on the carriage adapted to over-ride said stops when the carriage is travelled in letter spacing movement.
